HIS ATTORNEYS.

UNITED STATES PATENT OFFICE.

JAMES MCBRIDE, OF NEW YORK, N. Y., ASSIGNOR TO JAS. MCBRIDE FLOORING CO., INC.,
A CORPORATION OF NEW YORK.

PARQUETRY AND FLOORING.

Application filed May 15, 1926. Serial No. 109,299.

This invention relates to parquetry and flooring and has for its principal object the provision of means whereby flooring sections may be prepared as separate finished sections of parquet and other types of hard-wood flooring, may be shipped in strips or panels of sizes convenient to handle, and quickly and easily laid. By this procedure the usual operations of scraping, sanding, 5 varnishing, rubbing, etc., after laying, are eliminated, thus greatly reducing the cost 10 of such flooring. This also makes it possible to utilize odd or short lengths of flooring strips which otherwise would have been discarded or used for firewood.

One object of this invention is to provide a system of inter-connected air passages underneath the flooring to permit the circulation of air thereunder and to withdraw any 20 moisture laden air from the flooring and sub-flooring or the spaces between the same.

Further objects and advantageous features of the invention will be apparent from the following specification and the scope of the 25 invention will be pointed out in the appended claims.

My invention will be described hereinafter as embodied in a section of flooring to be laid on a wooden sub-flooring as well as on 30 a concrete sub-flooring, but the invention is not to be construed as being limited to the adaptations herein disclosed. By simple modifications the herein described flooring sections may be laid directly on the floor 35 beams or on sleepers set in concrete or in the usual cinder fill.

In the drawings, Fig. 1 is a plan view of two adjacent flooring sections embodying my 40 invention.

Fig. 2 is a bottom view of a flooring section.

Fig. 3 is a sectional view of part of a 45 flooring showing the means used to join adjacent sections and the method of securing the sections to the sub-flooring.

Fig. 4 is a sectional view of parts of two adjacent sections showing another method of joining the sections.

The flooring strip or section 1 illustrated 50 in Fig. 2 may be and is preferably made approximately as long as the room to be floored, or as long as practical and of convenient width, such as, for example, six strips of hardwood flooring material of ordinary width. The strips of flooring material

are preferably treated or impregnated with a water-proofing material before being assembled and finished. In this way the pores of the wood are sealed after kiln drying so that moisture which may subsequently be 60 present in the sub-flooring will not cause the finished flooring to warp, check or expand. The strips are preferably fastened together by glue or other cement as is usual in cabinet work, the glue being allowed to set under 65 heavy lateral pressure.

The section may comprise any suitable number of pieces of the same or different kinds of wood of varying and comparatively short lengths, glued or otherwise fastened 70 together, as above described, to form sections of the desired dimensions and obviously may be inlaid with wood of various tones or colors, having an appropriate arrangement of pieces to form ornamental floor designs. In order to prevent the strips from separating during transportation and to reinforce the sections laterally when laid, wooden cross pieces 2 extending across the under sides may be used. These pieces are 75 preferably fitted into cross rabbets or grooves cut into the under sides of the sections and lie flush therewith. They may be glued or otherwise fastened in place.

A number of grooves or air channels 3 are 80 cut into the underside of each section 1, and preferably extend diagonally across the bottom surfaces of the section as shown in Fig. 2. The lateral margins of the under sides 85 of the sections, and, if desirable, the margins at the ends of the section may be recessed or rabbeted as shown at 4, thereby forming 90 passages to connect the slots 3. Thus each section is provided with an underlying system 95 of inter-connected air channels, as indicated by dotted lines in Fig. 1. At desired points in the flooring holes 5 may be drilled through the section so as to form an outlet from the grooves or air channels 3.

In the preferred form a perforated brass 100 plug 6 is fitted into such holes, thus allowing the free and easy exit and circulation of air from beneath the flooring. If it should become desirable to remove the moisture laden air from beneath the flooring, a vacuum producing means may be connected with the hole 5 containing the perforated plug 6, and the air so withdrawn, or hot air under pressure, may be forced into the holes thereby 105 110

drying out the space between the flooring and sub-flooring.

In the preferred form of the flooring the lateral faces of adjacent sections have cut therein small male and female corrugations as indicated at 7. It is possible with this construction to accurately align adjacent sections and insure evenly matching sections of the flooring, thereby eliminating the necessity of planing the margins of adjacent sections. As an alternative method of aligning adjacent sections the construction shown in Fig. 4 may be used. This consists of cutting corresponding grooves in the lateral edges of adjacent sections and inserting a strip 8 of steel or other thin material therein.

When the flooring sections are to be laid on a sub-flooring of concrete, expansion screws or bolts 9 may be used to secure the sections to the concrete sub-flooring. When the sub-flooring is of wood, ordinary wood screws, as illustrated in Fig. 4, may be employed. In either case, it is desirable to countersink the heads of the screws and to drive into the countersunk holes wooden dowels 10 so that they may be flush with the surface of the floor.

When the flooring sections are to be laid upon a concrete or similar sub-flooring, it is desirable that the surface of this flooring be treated with a suitable water-proofing material and a layer of asbestos or asbestos felt interposed between the sub-flooring and the sections of the finished flooring herein described.

Having described these embodiments of my invention what I claim and desire to protect by Letters Patent is:

1. A section of flooring comprising, a plurality of strips of flooring material cemented together to form sections or panels of convenient width for handling and having connecting grooves cut in its underside and provided with a plurality of holes connecting said grooves with the surface of the flooring to form passages for the circulation of air after said flooring is laid.

2. A section of flooring comprising, a plurality of strips of flooring material cemented together to form sections or panels of convenient width for handling and having air channels comprising grooves cut in its underside, the lower margins of said section being recessed to form connecting passages for said channels, said section having a plurality of holes connecting said channels with the surface of the flooring.

3. A section of flooring comprising, a plurality of strips of flooring material united by a suitable cement to form sections or panels of convenient width for handling and

having a plurality of grooves cut diagonally across its underside and also provided with recessed lower edges to form connecting passages for said grooves, said section being provided with holes connecting said channels with the surface of the flooring and perforated caps inserted in said holes flush with the upper surface of said section.

4. A section of flooring provided with a system of interconnected air passages comprising grooves cut in its under side and provided with a plurality of holes connecting said system with the surfaces of the flooring, the edges of said section being provided with means for aligning adjacent sections.

5. A section of flooring provided with a system of interconnected air passages comprising grooves cut in its under side and provided with a plurality of holes connecting said system with the surface of the flooring, and the edges of said section being provided with corrugations adapted to coact with similar corrugations on adjacent sections, to align the same.

6. A section of flooring having a plurality of air channels comprising grooves cut in its under side, the lower margins of said section being recessed to form connecting passages for said channels, said section having a plurality of holes connecting said channels with the surface of the flooring, and the edges of said flooring being provided with means for aligning adjacent sections.

7. A section of flooring having its lower margins recessed and having a plurality of saw cuts extending diagonally across its under side and connecting with said recessed margins, said section being provided with holes drilled therethrough and connecting with said cuts, the lateral faces of said sections being provided with corrugations adapted to coact with similar corrugations on adjacent sections to align the same.

8. A section of flooring comprising, a plurality of strips of flooring material cemented together to form sections or panels of convenient width for handling, transverse reinforcing strips set into the underside of said longitudinal strips and cemented thereto, said reinforcing strips being flush with the under surface of said panels, the underside of said panel being provided with a plurality of air channels comprising grooves cut in its underside, said grooves passing through said reinforcing strips, the lower margins of said sections being recessed to form connecting passages for said channels and said section having a plurality of holes connecting said channels with the surface of the flooring.

Signed this 13th day of May, 1926.
JAMES McBRIDE.
